PROTECTIVE CLOTHING

Carroll P. Krupp, Akron, Ohio, assignor to The
B. F. Goodrich Company, New York, N. Y., a
corporation of New York

Application December 13, 1943, Serial No. 514,007

9 Claims. (Cl. 2-82)

1

This invention relates to protective clothing and especially to suits of water-tight construction substantially enclosing the wearer's body, including flotation suits.

The invention is useful especially in the construction of water-tight suits such, for example, as may be used for fording streams or by mariners immersed in the ocean during an emergency. Also, the invention is applicable in many of its features to other forms of protective clothing such as sleeping bags, sports clothing, and other complete or partial body coverings.

Principal objects of the invention are to provide clothing effectively protecting the wearer's body against objectionable exposure; to provide watertightness of the clothing; to provide convenience of donning and doffing the clothing; to provide for sealing an opening in the clothing; to provide for admitting a portion of the wearer's body into the clothing; and to provide simplicity of construction, convenience of manufacture, and convenience and effectiveness of operation.

Other objects of the invention are to provide comfort to the wearer; to provide for sealing a neck opening in the clothing in a relatively comfortable manner to the wearer; and to provide for conveniently adjusting and maintaining the clothing positioned at the neck of the wearer in sealing relation therewith.

These and other objects and advantages of the invention will be apparent from the following description.

In the accompanying drawings, which form a part of the specification and in which like numerals are employed to designate like parts throughout the same,

Fig. 1 is a side view of a flotation suit including a headpiece, and constructed in accordance with and embodying the invention, parts being broken away,

Fig. 2 is a front view of the suit showing a neck opening and sealing arrangement in the open condition, parts being broken away,

Fig. 3 is a section taken along line 3-3 of Fig. 2,

Fig. 4 is a section taken along line 4-4 of Fig. 1,

Fig. 5 is a view like Fig. 1 showing a modified construction of the suit, parts being broken away,

Fig. 6 is a section taken along line 6-6 of Fig. 5,

Fig. 7 is a view from above, the suit showing the modified neck opening and sealing arrangement in the open condition, parts being broken away, and

2

Fig. 8 is a section taken along line 8-8 of Fig. 7, parts being broken away.

In the illustrative form of the invention shown in Figs. 1 to 4, inclusive, the flotation suit having an opening for accommodating the neck of the wearer is made of flexible material such, for example, as fabric textile material having a substantially impervious coating or impregnation of resilient rubber or other rubber-like material, which flexible material possesses the desired characteristics of relatively light-weight, strength, and water-tightness. The suit preferably substantially encloses the wearer's body and comprises a torso covering 10, arm coverings 11 and 12 and leg coverings, and may include a headpiece 13, all of such parts being united at adjacent margins as by sewing, or a suitable adhesive such, for example, as rubber cement, or both. The headpiece 13 may have a fullness at the nape of the wearer's neck for facilitating head movement. Gloves and boots may also be provided and similarly united with the arm and leg coverings for protecting the hands and the feet of the wearer.

The torso covering 10 in the upper reaches of its continuously extending front portion may have considerable fullness at 14, like a bag or pouch, for defining the relatively large extent of the neck opening and sealing arrangement which facilitates admitting the wearer's body therethrough and conveniently donning and doffing the suit. Such fullness of the torso covering also facilitates including auxiliary flotation apparatus and other articles within the suit which the wearer may desire to protect against the water.

The neck opening and sealing arrangement includes, as shown especially in Figs. 1 to 4, a substantially solid or non-inflatable sealing pad or strip element 15 of relatively soft, compressible and yieldable material such, for example, as resilient, sponge rubber or other rubber-like material having cushioning characteristics by virtue of its resiliency, the pad element 15 having desirably a substantially impervious, relatively smooth coating or covering of suitable resilient rubber-like material for preventing absorption of water and such element is constructed so that it presents a uniform, non-devious inner sealing face to the wearer's neck. The pad element 15 including tapered ends 16 and 17 may be molded and vulcanized in the form of a split annular ring of sufficient extent to completely embrace the neck, and the tapered ends 16 and 17 are in overlapping relationship with one another for the closed condition of such neck opening arrangement.

For positioning the pad element 15 for effective sealing action, such element is mounted at the inside of a margin 18 of the opening and may be attached partially along its extent to such margin at the back of the torso covering 10 as by a suitable adhesive. The margin 18 comprises a folded strip or flattened tube 20 of suitable substantially water-tight, flexible fabric textile material extending continuously about the opening and attached as by sewing, or a suitable adhesive, or both along its lower marginal portion 24 to a margin 19 of the opening in the torso covering. The material of the flattened tube 20 may be more flexible and lighter in weight than that of the torso covering to facilitate puckering into a multiplicity of relatively small, closely contacting, flat folds positionable against the pad element.

A flexible draw-string 21 of braided linen cord, for example, is disposed within the flattened tube 20, as shown especially in Figs. 3 and 4. The end portions of the draw-string 21 extend through an aperture in the tube 20 at the front of the torso covering and desirably extend through a suitable quick-release clamping member 22 whereby the tube 20 may be puckered substantially along its extent by tautening the draw-string to obtain the closed condition of the neck opening arrangement and to deform and retain the pad element at and about the wearer's neck in a cushioning manner for sealing relation therewith. Other means such, for example, as a strap and fastener may be used to retain the pad element in its closed condition at the neck and to coat substantially in the manner of the draw-string 21 within the tube 20 in applying continuity of external compressive force to the pad element along the extent of the latter.

For further protecting the wearer the headpiece 13 may be attached along its lower margin 23 to the torso covering and preferably at the outside of the neck opening arrangement, which construction promotes additional sealing at the opening while permitting such neck opening arrangement to be in its closed condition whether or not the headpiece be mounted on the wearer's head. The margin of the opening in the headpiece is adapted to conform to the contour of the face and neck and to fit snugly thereagainst when the headpiece is mounted on the head.

In donning the flotation suit and having the neck opening arrangement in the open condition, the wearer's body is inserted feet first through the neck opening. When the legs, arms and torso are positioned within the suit, the sealing pad element 15 is arranged about the neck such that the tapered ends 16 and 17 are in overlapping relation, and next the headpiece may be mounted on the head. To obtain the closed condition of the neck opening arrangement, the draw-string 21 is tautened by pulling its end portions through the clamping member 22 thereby puckering the tube 20 and positioning the latter against the pad element 15 in sealing relation therewith. The draw-string is tautened to an extent such that it is embedded partially in the yieldable material of the pad element and such that the pad element 15 is maintained in a cushioning manner at the wearer's neck adjacent the jaw without undue pressure against the neck, the material of the pad element presenting a uniform, non-devious sealing face to the neck. By virtue of the yieldability and resiliency of the sponge rubber material, the pad element fits snugly about and conforms uniformly throughout its extent to the contour of the wearer's neck whereby continuity of cushioning and sealing action is obtained. The

10
15

5 relatively thick pad element as compared to the flexible margin 18 accommodates variations in tautness of the draw-string 21 without substantial discomfort to the wearer.

In doffing the suit the tautness of the draw-string is released by operation of the clamping member 22 permitting the tube 20 to be extended from its puckered condition until the neck opening arrangement is in the open condition, as shown especially in Fig. 2. The headpiece and pad element are removed from the head and neck, respectively, and the wearer's body withdrawn through the neck opening.

For the modified construction of the suit shown in Figs. 5 to 8, inclusive, the neck opening and sealing arrangement includes a substantially solid or non-inflatable sealing pad element 25 disposed at the back of the opening and a second substantially solid or non-inflatable sealing pad element 26 at the front thereof, the respective pad elements being of suitable resilient, sponge rubber-like material having cushioning characteristics and having a suitable impervious coating or covering.

25 The sealing pad element 25 including tapered ends 27 and 28 partially embraces the wearer's neck and may be mounted within a back portion 29 of a folded strip or flattened tube 30 of suitable flexible, substantially water-tight, fabric textile material, the tube 30 extending about the neck opening and being attached as by sewing, or a suitable adhesive, or both along its lower marginal portion 31 to the margin 19 of the opening in the torso covering 10. The second pad element 30 including tapered ends 33 and 34, which element may be arcuate in form to facilitate its conforming to the contour of the neck, is attached partially to a front portion 32 of the tube 30, and is constructed and arranged to embrace the remainder of the neck. The tapered ends 33 and 34 cooperate with the adjacent tapered ends 27 and 28 by an overlapping relation therewith to complete the sealing encirclement of the neck by the pad elements 25 and 26, as shown especially in Figs. 5 and 6.

40 The pad element 26 may include flared or curved projecting portions 35 and 36 along the tapered ends 33 and 34 for conforming to the contour of the lower jaw of the wearer to promote additional sealing by the neck opening arrangement. For facilitating positioning the pad element 26 against the wearer's neck for coacting with the other pad element 25, the pad element 26 may be provided with a relatively narrow, arcuate band portion 37 of suitable resilient rubber-like material interconnecting the tapered ends 33 and 34 whereby such pad element becomes substantially annular in form, as shown especially in Fig. 7, and defines an opening 38 for receiving the neck.

45 The draw-string 21 is disposed within the flattened tube 30 and is arranged to press against the back of the pad element 25. End portions of the draw-string extend through an aperture at the front portion 32 of the tube and may extend through the clamping member 22 to facilitate tautening the drawstring for positioning the pad elements 25 and 26 in coacting sealing relation at the neck.

50 In donning the modified suit and having the neck opening arrangement in the open condition, the wearer's body is inserted feet first through the opening and positioned within the suit. The head is inserted through the opening 38 in the annular pad element 26, and such element in-

60

65

70

75

cluding the curved projecting portions 35 and 36 is disposed adjacent the lower jaw, the band portion 37 being in a slightly tensioned condition and extending about the back of the neck thereby facilitating maintaining the pad element 26 in position for coacting with the other pad element 25. The draw-string 21 is tautened thereby puckering the flattened tube 38 into a multiplicity of closely contacting flat folds along its extent intermediate the tapered ends 27 and 28 of the pad element 25 and positioning such tube against the front pad element 26 in sealing relation therewith. Tautening the draw-string also positions the tapered ends 27 and 28, 33 and 34 of the pad elements 25 and 26 in overlapping sealing relation and maintains such elements in a cushioning manner about the neck without objectionable pressure against the neck whereby a circumferentially uniform, non-devious sealing face is presented to the neck for the closed condition of the arrangement. The sealing face of the pad elements conforms to the contour of the neck by virtue of the yieldability and resiliency of the rubber material. If desired, the headpiece 13 may be mounted on the wearer's head for further protection.

The modified suit may be doffed conveniently by removing the headpiece from the head and releasing the tautness of the draw-string such that the neck opening arrangement may be returned to the open condition. The pad element 26 is slipped over the head and the wearer's body withdrawn through the opening from the suit.

Variations may be made without departing from the scope of the invention as it is defined in the following claims.

I claim:

1. Protective clothing having an opening for accommodating the wearer, said clothing at the opening comprising a margin of flexible material and a sealing pad element partially attached to said margin leaving a portion of said pad element unattached to said margin so as to be freely adjustable with respect thereto, said pad element comprising a strip of relatively yieldable material presenting an inner sealing face of the yieldable material to the wearer.

2. Protective clothing having an opening for accommodating the neck of the wearer, said clothing at the opening comprising a margin of flexible material and a sealing pad element partially attached at the inside of said margin leaving a portion of said pad element unattached to said margin so as to be freely adjustable with respect thereto, said pad element comprising resilient material relatively thick as compared to the flexible material of said margin, said resilient material presenting a uniform non-devious sealing face of the resilient material to said neck.

3. Protective clothing having an opening for accommodating the neck of the wearer, said clothing at the opening comprising a margin of flexible material, and a sealing pad element of relatively yieldable material at said margin embracing said neck and positionable adjacent the lower jaw of the wearer, said pad element including opposite upwardly flared portions being constructed and arranged to conform to the contour of said jaw, said yieldable material presenting an inner sealing face of the yieldable material to said neck.

4. Protective clothing having an opening for accommodating the neck of the wearer, said clothing at the opening comprising a margin of flexible fabric material, a sealing pad element including tapered ends of relatively resilient

sponge rubber-like material and partially attached at said margin at the region of the back of said neck for embracing the latter leaving forward portions including said tapered ends of said pad element unattached to said margin so as to be freely adjustable with respect thereto, said tapered ends being positionable in overlapping sealing relation with one another, said rubber-like material presenting an inner sealing face of the rubber-like material to said neck, and means for positioning said pad element at said neck in sealing relation therewith.

5. Protective clothing having an opening for accommodating the neck of the wearer, said clothing at the opening comprising a margin of flexible fabric material including a front portion and a back portion, a sealing pad element including tapered ends and attached at the inside of said back portion for partially embracing said neck, a second sealing pad element including tapered ends and partially attached at the inside of said front portion with the latter said tapered ends extending rearwardly unattached to said margin so as to be freely adjustable with respect thereto for embracing the remainder of the neck, said tapered ends of the first said pad element being positionable in overlapping sealing relation with said tapered ends of said second pad element, the pad elements, comprising relatively resilient sponge rubber-like material presenting an inner sealing face of the sponge rubber-like material to the neck, and means for positioning said pad elements at the neck of the wearer in sealing relation therewith.

35 6. Protective clothing having an opening for accommodating the neck of the wearer, said clothing at the opening comprising a margin of flexible fabric material including a front portion and a back portion, sealing pad elements attached at the inside of said front portion and said back portion, a margin of a pad element being unattached to said margin of said opening so as to be freely adjustable with respect thereto and tapering to provide a sealing surface cooperative with the other pad element for sealing relation therewith, said pad elements comprising relatively soft compressible material presenting an inner sealing face of said compressible material to the neck, and means for positioning said pad elements at the neck of the wearer in sealing relation therewith.

7. Protective clothing having an opening for accommodating the neck of the wearer, said clothing at the opening comprising a margin of flexible material including a front portion of said material positionable about the neck of the wearer, and a sealing pad element at the inside of said margin unattached to said margin throughout the major part of the extent of said pad element so as to be adjustable with respect to said margin and conformable to said neck, said pad element comprising resilient material relatively thick as compared to the flexible material of said margin, and said resilient material presenting a substantially uniform non-devious sealing face of the resilient material to the neck of the wearer.

8. Protective clothing having an opening for accommodating the neck of the wearer, said clothing at the opening comprising a margin of flexible material including a front portion of said material having substantial fullness and contractible into a multiplicity of closely contacting folds positionable about the neck of the wearer,

a sealing pad element at the inside of said margin unattached to said margin throughout the major part of the extent of said pad element so as to be adjustable with respect to said margin and conformable to said neck, said pad element comprising resilient sponge rubber-like material relatively thick as compared to the flexible material of said margin, said sponge rubber-like material presenting a substantially uniform non-

devious sealing face of the sponge rubber-like material to the neck of the wearer.

9. Protective clothing as defined in claim 8 in which said sealing face of the pad element is relatively flat transversely of said pad element and is of transverse width not less than the thickness of said pad element providing a substantial sealing area at the neck of the wearer.

CARROLL P. KRUPP.
